(57) **CLAIM**

The ornamental design for a rock light housing, as shown and described.

DESCRIPTION

FIG. 1 is a perspective view of a rock light housing showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings depict portions of the rock light housing that form no part of the claimed design. The unshaded surfaces adjacent to broken lines form no part of the claimed design.
